REFRIGERATING APPARATUS

Filed May 11, 1929

Inventor:
George J. Cooke

By Cheever, Cox & Moore, Atty.

UNITED STATES PATENT OFFICE

GEORGE J. COOKE, OF CHICAGO, ILLINOIS

REFRIGERATING APPARATUS

Application filed May 11, 1929. Serial No. 362,399.

This invention relates to refrigerating systems in general and particularly to the process and apparatus involving the compression of refrigerant as distinguished from the absorption type of refrigerators. More specifically the invention relates to a compression type of apparatus which uses ammonia as the refrigerant.

In the conventional type of ammonia refrigerating apparatus it has been the custom to use an iron or steel pipe instead of seamless copper tubing, because ammonia would quickly decompose copper pipe. Iron and steel pipe requires the use of many elbows, T's, and other fittings, which increases the cost of the installation as well as the cost of the material itself. This kind of pipe is never clean and smooth on the inside as it contains scales and other foreign particles, and it 20 rusts very quickly.

The present invention eliminates all the inherent disadvantages of the conventional material now used, and its primary object is to provide a refrigerating apparatus which is 25 designed to cut down or eliminate a great number of elbows, T's, unions and other fittings during the construction and assembling of the apparatus.

Another object is to provide an apparatus 30 in which the coils in the evaporator, the supply and return lines, and the coils in the condenser may be made of the same kind of material.

Another object is to provide an apparatus 35 in which the coils and connecting pipes are made from bendable seamless material.

A still further object is to provide an apparatus which has the evaporator, condenser coils, and the connecting pipes therefor made 40 of block tin pipe which bends easily and which is always smooth and clean and will not rust.

The invention comprises in general a condenser in which the condenser coil is spirally arranged. This condenser coil is made of block tin pipe and the lower end of the coil 45 discharges into a fluid supply chamber. A block tin supply line communicates with this chamber for carrying the liquid ammonia to 50 the coils arranged in the evaporator. The

evaporator and the supply line can be made continuous and then bent around to form the return line which leads to the compressor. If the refrigerator is of the dual type, such as is shown in the drawing of my co-pending application, Serial No. 362,398, filed May 11, 1929, the supply line and the return line also lead to the coils in the ice cream freezer. The return line from the freezer connects to a T, which also connects with the return line from the evaporator. A valve is arranged in the supply line for selectively effecting communication between either the evaporator or the ice cream coils. The coils and return line to the ice cream freezer are 65 also made of block tin pipe.

The accompanying drawing illustrates a selected embodiment of the invention and the view is a vertical section through the apparatus.

Referring to the drawing, 10 designates a supply line which is made of block tin pipe and in which the compressed refrigerant is carried in liquid form to the expansion or evaporator coils 11. These coils are arranged in the brine tank 12 and are also made of block tin pipe. The brine tank 12 is suitably arranged in the refrigerating chamber 13, as clearly shown in Fig. 1. A chamber 14 is arranged in the tank 12 for the reception of trays 15 for the manufacture of ice cubes. While the expansion coils 11 are shown arranged in the brine tank 12, it is, of course, understood that the brine tank 12 may be omitted and the coils used in direct expansion in a manner well known in the art without having the coils in brine.

A supply line 16 made of block tin pipe is connected to the line 10 and communicates with the block tin pipe coils 17 in the chamber 18 of the ice cream freezer 19. A return line 20, which is also made of block tin pipe and may be made integral with the supply line 16 and the coils 18, carries off the refrigerant in the form of a gas and leads to a T 21 on the main return line 22. A return line 23, which is made of block tin pipe and which may be made integral with, or be an extension of, the coils 11, also connects with the T 21 for carrying off the gas refrigerant.

The refrigerant used is ammonia (NH_3) and the parts are substantially arranged in the manner disclosed and claimed in the aforesaid co-pending application.

5 A valve 24 is provided between the main feed line 10 and the ice cream freezer feed line 16. This valve selectively controls the flow of liquid ammonia to either the main evaporator or to the ice cream freezer, as desired. The gas in the return line 22 leads to the compressor 26, where it is compressed and then enters the condenser coils 51, which are also made of block tin pipe. The condenser coils are arranged in the condenser casing 52. The coils are cooled by means of water in the condenser casing, and after the compressed fluid is sufficiently cooled it passes into the supply line 10 where it is again circulated throughout the system in the manner set forth in the said co-pending application.

25 By using block tin, or substantially pure tin, an alloy containing a high percentage of pure tin pipe for the supply and return lines and also for the coils, any decrease in conductivity which may be caused by any oil entering the expansion coils is overcome by the increased conductivity of block tin. Block tin has a very great conductivity and 30 produces a very desirable result particularly over iron pipe, which is used exclusively in ammonia refrigeration machines. Block tin pipe will not rust, is easily bent, eliminates the threading of the pipes and many fittings and joints. It has a silver color which adds to the appearance of the installation and it molds as clean as a rifle barrel on the inside, which is a very important feature in automatic machines. Copper pipe cannot be successfully used in ammonia systems as the ammonia would decompose the copper pipe in a 35 very short time. Iron and other kinds of pipe heretofore used scale and rust on the inside, which renders this kind of pipe very 40 objectionable for an automatic machine of the type disclosed in the aforesaid application. In fact, the cause of the failure of almost every type of automatic machine is due to the dirty pipe which is used in connection 45 therewith.

50 For the ordinary domestic type of refrigerators having up to 15 cubic feet content and the equivalent of 100 pounds of ice per day, it has been desirable to use $\frac{1}{8}$ inch block tin pipe for the supply or liquid line, and $\frac{1}{4}$ inch block tin pipe for the return line, while the coils in the condenser and the evaporator are substantially $\frac{1}{8}$ inches diameter. For the larger boxes the diameter of 55 the pipe runs from $\frac{1}{8}$ to $\frac{5}{8}$ inch and varies proportionately with the size of the cubical contents of the refrigerator and also the type of system used. In any case the block tin pipe will have comparatively thin side 60 walls.

Many experiments had been made until commercial block tin pipe was discovered to replace all other kinds of piping for ammonia refrigerating systems. Outside of the present invention, commercial block tin pipe 70 was never used in ammonia refrigerating systems. The manner in which block tin pipe can be handled, its clean smooth surfaces, and its resistance against corrosion and fouling, renders block tin pipe the most preferable 75 of all kinds of piping and tubing for use in small ammonia refrigerating systems containing a safe charge of ammonia.

The use of seamless block tin pipe or tubing is, of course, only practicable where a 80 small amount of refrigerant is used. In a refrigerating system such as disclosed in the aforesaid application, a very small amount of ammonia is used in comparison with the conventional refrigerating systems. For example, the copending application points out that only three and one-half ounces of ammonia is used on a one-sixth ton machine (a one-sixth ton machine being the equivalent to the melting of one-sixth of a ton of ice 90 per day).

95 Block tin pipe is not affected by ammonia, cuts the cost of installation considerably, and eliminates dirt, flakes, rusts, and other foreign matter from clogging the pipes or the expansion valve. Expansion valves have a relatively small opening and a relatively small amount of dirt or rust would quickly cause the operation of the machine to fail.

100 It is to be understood however, that the term "block tin pipe" means pipe which is made of pure tin or substantially pure tin or an alloy containing a high percentage of tin. It is preferable however, that the pipe used is what is known as commercial block 105 tin pipe.

110 Changes may be made in the form, construction, and arrangement of the parts without departing from the spirit of the invention or sacrificing any of the advantages 115 thereof, and the right is hereby reserved to make all such changes as fairly fall within the scope of the following claims.

115 The invention is hereby claimed as follows:

1. In an ammonia refrigeration system, an expansion coil, condensing means including a condenser coil, a block tin pipe supply or liquid line connecting said condenser coil and said expansion coil, and a block tin pipe 120 return line connecting said expansion coil and said condensing means, said block tin supply and return lines having relatively thin side walls and being no greater than five eighths of an inch in diameter.

125 2. A refrigerating apparatus comprising in combination, means to compress a refrigerant, a condenser coil made of block tin pipe having a diameter no greater than five-eighths of an inch, a block tin pipe supply or liquid 130

line leading from said condenser coil and having a diameter not exceeding one-fourth of an inch, an expansion coil made of block tin pipe and communicating with said supply line, and a block tin pipe return line operatively connected to said expansion coils and connected to said compressor mechanism.

3. A refrigerating apparatus comprising in combination, means to compress a refrigerant, a condenser coil made of block tin pipe, a block tin pipe supply line leading from said condenser coil, an expansion coil made of block tin pipe and communicating with said supply line, and a block tin pipe return line operatively connected to said expansion coils and connected to said compressor mechanism, all of said pipe ranging from one-eighth inch to five-eighths inch in diameter and having comparatively thin side walls.

In witness whereof, I have hereunto subscribed my name.

GEORGE J. COOKE.
